UNITED STATES PATENT OFFICE.

MILTON THAYER NEWMAN, OF MIAMI, FLORIDA.

ATTACHMENT FOR SAFETY RAZORS.

Application filed June 9, 1922. Serial No. 567,119.

To all whom it may concern:

Be it known that I, MILTON THAYER NEWMAN, a citizen of the United States, residing at Miami, in the county of Dade and State of Florida, have invented certain new and useful Improvements in Attachments for Safety Razors, of which the following is a specification.

This invention relates to razors, and the primary object of the invention is to provide an attachment for safety razors which is so constructed as to effectively hold the blade against movement during all adjustment of the razor, and to prevent the clogging up of the guard plate.

In use of safety razors of the character disclosed in U. S. Letters Patent 775,135 granted November 15, 1904, on the invention of King C. Gillette, hereinafter termed "original Gillette type," difficulty is experienced in shaving when the razor is adjusted for giving a close shave, due to the fact that the blade is loosened in the holder which permits movement or chattering of the blade, causing the cutting of the skin of the user. In an improved razor disclosed in Patent #1,328,024, issued Jan. 13, 1920, on the invention of Edward R. Wharton, the guard plate of the original Gillette type is modified to prevent clogging of the guard plate and to permit adjustment of the blade to be had without the loosening thereof in the holder. While this safety razor of the new type accomplishes its purpose, the improvement cannot be readily incorporated in the razor of the original Gillette type, thus necessitating the buying of a complete new razor.

It is therefore another prime object of this invention to provide an insert for connection with safety razors of the original Gillette type for effectively spacing the blade from the guard plate to prevent clogging of the plate and to permit a wide range of adjustment of the blade to be had relative to the guard plate without the loosening of the blade in the holder.

A still further object of the invention is to provide an improved attachment for safety razors of the above character, which will be durable and efficient in use, one that will be simple and easy to manufacture, and one which can be readily associated with the safety razor in an expeditious manner.

With these and other objects in view, the invention consists in the novel construction,

arrangement and formation of parts, as will be hereinafter more specifically described, claimed and illustrated in the accompanying drawings, forming a part of this specification, in which drawings:

Figure 1 is an edge elevation of a safety razor, showing the improved attachment or insert incorporated therewith prior to the adjustment of the blade.

Figure 2 is a similar view showing one adjusted position of the blade.

Figure 3 is a similar view showing another adjustment of the blade.

Figure 4 is a section taken on the line 4—4 of Figure 1, showing the improved attachment or insert in plan.

Figure 5 is an edge elevation of a safety razor, showing the modified type of attachment or insert incorporated therewith.

Figure 6 is a detail perspective view of the modified form of attachment or insert.

Figure 7 is an edge elevation of a safety razor, showing a still further modified type of insert or attachment incorporated therewith.

Figure 8 is a section taken on the line 8—8 of Figure 7, showing a further modified form of the insert or attachment in plan.

Referring to the drawings in detail, wherein similar reference characters designate corresponding parts throughout the several views, the letter A generally indicates a safety razor of the original Gillette type; B, the novel insert or attachment therefor; C and D, the modified forms of inserts or attachments.

While three forms of the improved attachment or insert have been illustrated, it is to be understood that other forms may be made without departing from the spirit or scope of the invention.

The razor A is, as stated, of the original Gillette type and includes the elongated arcuate shaped cap plate 10, which normally overlies the elongated arcuate shaped guard plate 11 with the concavity of the former confronting the convexity of the latter. The cap plate 10 supports the inwardly extending pins 12 for the shaving blade 13, and these pins are adapted to extend through the blade in the ordinary manner and through the guard plate 11. Adjustment is had between the guard plate 11 and cap plate 10 in the ordinary manner, and the cap plate 10 can support the inwardly extending centrally disposed stud 14 on which

can be threaded the handle 15. Thus, by turning the handle, the blade 13 is adapted to be flexed and held rigidly in place between the cap plate 10 and the guard plate 11. The guard plate has its lateral edges provided, of course, with the usual guard teeth 16.

In all of the forms of the improved attachment or insert, the same is adapted to be placed between the guard plate 11 and the blade 13, as clearly shown in Figures 1 to 3 inclusive, 5 and 7.

The improved insert or attachment B is preferably formed of flexible spring material, such as steel and consists of an elongated plate, having its ends curved, so as to conform to the general configuration of a Gillette safety razor blade. This plate is adapted to extend at least the full length of the guard plate 11, and is of such a width that its lateral edges will lie inwardly of the guard teeth 16, as clearly shown in Figure 4 of the drawings and inwardly of the longitudinal edges of the cap plate 10, as shown in Figures 1 and 2. This plate 17 is provided with a pair of longitudinally extending corrugations 18 on opposite sides of its longitudinal center with their convexities engaging the guard plate, and the longitudinal or lateral edges of the plate are preferably struck downwardly at an incline as indicated by the reference character 19. At the longitudinal center of the plate 17, suitable openings 20 and 21 are provided respectively for the guide pins 12 for the blade 13 and the adjusting stud 14.

In use of the attachment, the blade 13 is placed on the pins in the ordinary manner, after which the attachment B is placed on said pins and the guard plate 11 is moved into engagement with the attachment. The handle 15 can now be adjusted in the usual way. The attachment will first assume a position as shown in Figure 1 of the drawings, holding the blade 13 into intimate engagement with the longitudinal edges bounding the concavity of the cap plate 10. As the handle 15 is adjusted, the attachment and blade will be flexed, as shown in Figure 2 of the drawings, so as to arcuate into the cavity of the cap plate, bringing the cutting edges of the blade closer to the guard teeth 16. The handle can be adjusted until the plate 17 is flexed to such a position that the same assumes an arcuate configuration as shown in Figure 3 of the drawings. This, of course, brings the cutting edges of the blade 13 relatively close to the teeth 16 but at the same time spaces the cutting edges of the blade a sufficient distance away from the guard teeth to prevent the clogging up thereof by the beard of the user.

In the form C, the attachment consists of a rectangular shaped plate 25, which has a

length substantially equal to or more than the guard plate 11 and a width less than the width of the cap plate and guard plate so that the longitudinal edges of the plate 25 will lie well inwardly of the guard teeth 16 formed on the guard plate 11. This plate 25 is also formed of resilient material and is preferably formed of a plurality of relatively thin laminations 26. At the longitudinal center of the plate 25 is disposed a pair of openings 27 for the blade guide pins 12 and a central opening 28 for the adjusting stud 14. This attachment is placed on the razor in the same manner as the form A and adjustment can be had in the same manner. If it is found, however, that the blade 13 cannot be adjusted close enough to the guard teeth 16, certain laminations can be torn off of the plate 25, thus reducing the same in thickness.

In Figures 7 and 8 of the drawings is illustrated the form D of the attachment, which consists of the longitudinally extending spaced parallel bars 30, connected by transverse strips 31, which may be provided with openings 32 for the reception of the pins 12. The bars 30 may be of circular shape in cross section, if so desired, and it can be seen that these bars form fulcrum shoulders on which the blade can be flexed. This attachment also spaces the edges of the blades a sufficient distance from the teeth 16 to prevent the clogging up thereof as heretofore described. Adjustment of the blade 13 relative to the teeth 16 can be had by the turning of the handle 15.

From the foregoing description, it can be seen that an improved attachment has been provided for razors of the original Gillette type which will effectively permit a wide range of adjustment of the blade relative to the guard plate without the blade losing its rigidity or chattering within the holder, and which will effectively prevent the razor from clogging up, thus eliminating the necessity of taking the razor apart to clean the same during a shave.

Changes in details may be made without departing from the spirit or scope of this invention; but,

I claim:

1. The combination with a safety razor including a cap plate and a guard plate, the cap plate having a concave face confronting the guard plate, means for adjusting the plates relative to one another, and a flexible blade engaging said cap plate; of a flexible insert intermediate the guard plate and blade, acting upon said blade to arcuate the latter into the concavity of the cap plate and space the blade from the guard plate.

2. The combination with a safety razor including a cap plate and a guard plate, the plates having concave and convex faces, re-

spectively, confronting one another, means for adjusting the plates relative to one another, and a flexible blade engaging said cap plate; of a flexible insert intermediate the guard plate and blade, acting upon said blade to arcuate the latter into the concavity of the cap plate and space the blade from the guard plate.

3. The combination with a safety razor including elongated cap and guard plates, the cap plate having a concave face confronting the guard plate, means for adjusting the plates relative to one another, and a flexible blade engaging said cap plate; of a flexible insert relatively narrower than the cap plate, disposed intermediate the guard plate and blade, and acting upon said blade to arcuate the latter into the concavity of the cap plate and into intermediate contact with the longitudinal edges of the cap plate bounding said concavity.

4. The combination with a safety razor including elongated cap and guard plates, the plates having concave and convex faces, respectively, confronting one another, means for adjusting the plates relative to one another, and a flexible blade engaging said cap plate; of a flexible insert relatively narrower than the cap plate, disposed intermediate the guard plate and blade, and acting upon said blade to arcuate the latter into the concavity of the cap plate and into intimate contact with the longitudinal edges of the cap plate bounding said concavity.

5. The combination with a safety razor including elongated cap and guard plates, the plates having concave and convex faces, respectively, confronting one another, means for adjusting the plates relative to one another, and an elongated flexible blade relatively wider than said cap plate but relatively narrower than said guard plate dis-

posed in engagement with said cap plate and provided with longitudinal cutting edges outwardly of said cap plate; and an elongated flexible plate, relatively narrower than said cap plate, disposed between said blade and guard plate, and provided with longitudinally extending corrugations spaced equidistant from the longitudinal center of the flexible plate, the convex faces of which engage the guard plate, whereby upon movement of the cap and guard plates toward each other, the flexible blade will be primarily flexed into the concavity of the cap plate by engagement with the longitudinal portions of the flexible plate with the flexible blade adjacent the longitudinal edges of the cap plate, and upon further movement of the cap and guard plates, the central longitudinal portion of the flexible plate will engage the central longitudinal portion of the blade and aid in arcuating the blade into the concavity of the cap plate.

6. The combination with a safety razor including elongated cap and guard plates, the plates having concave and convex faces, respectively, confronting one another, means for adjusting the plates relative to one another, and an elongated flexible blade relatively wider than said cap plate but relatively narrower than said guard plate, disposed in engagement with said cap plate and provided with longitudinal cutting edges outwardly of said cap plate; of an insert initially engaging the blade at its face opposite to said cap plate and slightly inwardly of the longitudinal edges of the cap plate at spaced apart lines to arcuate the blade into the concavity of the cap plate and into firm engagement with the longitudinal edges of the cap plate bounding said concavity, when the cap and guard plates are moved toward each other.

MILTON THAYER NEWMAN.
